UNITED STATES PATENT OFFICE.

LEONARD JAMES ARON, OF LONDON, ENGLAND, ASSIGNOR TO X. L. ELECTRIC COMPANY LIMITED, OF LONDON, ENGLAND.

ELECTRIC-CLOCK SYSTEM.

1,144,885.

Specification of Letters Patent. Patented June 29, 1915.

Application filed September 30, 1912. Serial No. 723,184.

To all whom it may concern:

Be it known that I, LEONARD JAMES ARON, a subject of the King of England, residing at London, in England, have invented certain new and useful Improvements in Electric-Clock Systems, of which the following is a specification.

This invention relates to systems for electrically controlling or operating one or more time indicating devices from one or more master clocks which are mechanically driven and regulated by a pendulum or otherwise.

The present invention has for its object to provide a system of the above character which shall be more reliable in operation and less susceptible of interference than those previously proposed.

According to the present invention the actuating electric impulses transmitted by each of the master clocks of the system are successively opposite in sign so that a positive actuating impulse is succeeded by a negative impulse and the dial indicators of the system or relays controlling such dial indicators are so constructed that the proper progression of the dial indicators can only be effected by such alternately different impulses. Two or more entirely separate and independent systems of distribution conductors are provided for transmitting the impulses to the dial indicators and each of these distribution systems includes a master clock. Each dial indicator of the system or each relay controlling one or more dial indicators therefore receives two or more impulses of the same sign or in the same direction at each actuating instant, viz. one for each of the several master clocks, these several impulses being either simultaneous or successive and being each transmitted along an entirely independent distribution circuit.

It will of course be understood that each of the dial indicators of the system above described may be replaced by a suitable relay which controls a local circuit comprising one or more dial indicators. Such a relay may be provided with two or more actuating windings, that is to say one connected in each of the distribution systems, these several windings being either mounted on a common magnetic core or upon separate

cores arranged to influence a common armature. Alternatively the relay may be so constructed as to comprise a separate contact making or breaking mechanism for each of its several energizing windings or any other suitable arrangement may be adopted which will enable an actuating impulse from each of the several distribution systems to be transmitted to the local dial indicator circuit through the relay.

The invention is illustrated in the accompanying drawings, Figures 1 and 2 of which illustrate diagrammatically the connections and arrangements of systems embodying the invention, Figs. 3, 4 and 5 being similar diagrams illustrating in further detail the connections and arrangement of a portion of the apparatus shown in Fig. 2.

Referring now to Fig. 1, the clock system shown therein comprises two master clocks 1, 2, each having a rotating contact arm 3, 4, adapted to engage alternately with pairs of stationary contacts 5, 6 and 7, 8. The contacts 5, 6 of the master clock 1 are connected to the terminals of a sub-divided battery 9, the middle point of which is connected to one of the circuit conductors 10, the contacts 7, 8 of the master clock 2 being similarly connected to the terminals of a sub-divided battery 11, the middle point of which is connected to another circuit conductor 12. The contact arms 3, 4 of the master clocks 1 and 2 are both connected to a common conductor 13 which is preferably earthed.

The dial indicators 14 of the system may be of any of the numerous well-known constructions arranged to operate under impulses alternately opposite in sign; such for instance, as shown in Fig. 1 where 16 and 17 represent two actuating coils wound about a core 50, the coil 16 being connected between the conductor 10 and the earthed conductor 13, and the coil 17 similarly connected between the conductor 12 and the earthed conductor 13. A polarized armature 51 is pivotally supported in the gap of the core 50 and carries a pair of pawls 52 and 53 coöperating with ratchet wheels 54 and 55, respectively mounted on the indicator spindle 56 and a spindle 57 arranged

parallel thereto, said spindles being connected to move together by the gear wheels 58 and 59. The coils 16 and 17 are so wound on the core 50 that impulses of similar sign traversing the windings will move the armature in the same direction, so that after a positive impulse has traversed the winding 16 moving the armature 51 to actuate the indicator spindle through the respective pawl and associated parts, a later positive impulse traversing the coil 17 obviously will have no result.

The operation of this form of the invention is as follows:—The rotating contact arms 3, 4 of the master clocks 1 and 2 are arranged to engage either simultaneously or successively with pairs of corresponding contacts 5, 7 and 6, 8 in turn, the engagements thus effected causing the right and left sections of the batteries 9 and 11 to supply electric impulses to the conductors 10, 13 and 12, 13 respectively. The dial indicators 14, are so constructed that if an impulse has been transmitted from the subdivided battery 9 to the actuating winding 16 of these indicators a later similar impulse from the subdivided battery 11 due to the operation of the master clock 2 will traverse the other actuating winding 17 of the dial indicators 14, but will not cause any further progression in the indications given by these dial indicators. Each dial indicator receives two separate and distinct impulses from the batteries 9, 11 through the master clocks 1, 2 respectively, one of these impulses being supplied to the actuating winding 16 through the circuit conductor 10 and the other impulse being supplied to the actuating winding 17 of the dial indicators through the circuit conductor 12. In the event of failure of either of the master clocks 1, 2 or of the batteries 9, 11 the master clock or battery still remaining in operative condition will be able to continue the proper operation of the dial indicator system and, furthermore, the circuit conductors 10 or 12 or the subsidiary conductors connecting the circuit conductors 10 or 12 of the dial indicators may be broken at any point without interference with the working of the system. It will thus be seen that the arrangements for actuating the dial indicators are completely duplicated as regards the master clocks, batteries and conductors and as regards the dial indicators and their connections, so that a maximum of safety against interruption is provided.

Referring now to Fig. 2, a modification of the arrangement above described is illustrated having one or more or all of the dial indicators 14, each replaced by a relay device 18, having two actuating windings 19, 20 which are connected to the circuit conductors 10, 12 and to earth in a similar manner to the windings 16, 17 of the dial

indicators illustrated in Fig. 1. The relay devices 18 may each be arranged to control the supply of electric impulses from one or more independent sources to a local indicator circuit comprising a number of dial indicators 14. The operation and arrangement of this modification is very similar to that already described with reference to Fig. 1, except that in this case the duplication of the system is only carried as far as the relay devices 18. Beyond this point the circuit and operative parts are not duplicated.

Preferred forms of arrangements for connecting the relay device 18 to the local dial indicator circuit are indicated in Figs. 3, 4 and 5 of the drawings. In Fig. 3 the relay device 18 is shown as comprising a magnetizable core 21 provided with two actuating windings 19, 20 two of the terminals of which are connected together and earthed as indicated at 22, the remaining terminals 23, 24 of these windings being connected to the circuit conductors 10, 12 respectively. The movable member of the relay device comprises a permanently magnetized arm 25, attached to a spring support 26 and located in an air gap of the core 21. The magnetized arm 25 carries a head 27 which, when the core 21 is magnetized by an impulse traversing either the winding 19 or the winding 20, is arranged to close one or other of a pair of spring switches 28, 29 according as to whether the impulse is positive or negative. Two spring contacts one in each of these switches, are connected together to a conductor 30 forming one of the conductors of the local indicator circuit, the other spring contacts being connected to the terminals of the subdivided battery 31, the middle point of which is connected to a conductor 32 forming the other conductor of the local indicator circuit.

The operation of this form of the invention is as follows:—Assuming that a positive impulse has been transmitted to the circuit conductor 10, the actuating winding 19 of the relay device will be energized and the magnetized arm 25 will be attracted toward the left, thereby closing the spring switch 28 and connecting the left section of the subdivided battery 31 between the conductors 30, 32 so as to transmit an impulse to the dial indicators 14 connected thereto. A later positive impulse transmitted to the circuit conductor 12 will cause in a similar manner the actuating winding 20 of the relay device 18 to be energized.

The actuating windings 19, 20 are so wound that impulses of the same sign traversing these windings will cause similar movements of the magnetized arm 25, so that the later positive impulse above referred to will also cause the spring switch 28 to be closed and a second positive im-

pulse to be transmitted to the circuit conductors 30, 32.

The operation of the relay when a negative impulse reaches either the winding 19 or the winding 20 is precisely similar, except that the magnetized arm 25 is in this case deflected toward the right so as to close the spring switch 29 and connect the right section of the battery to the circuit conductors 30, 32.

Referring now to the arrangement shown in Fig. 4, the actuating windings 19, 20 of the relay device 18, instead of being mounted on a common core as shown in Fig. 3, are each provided with separate cores 33, 34. A permanently magnetized contact arm 35 is pivoted at 36 and maintained by springs 37 in such a position that when neither of the windings 19, 20 are energized, the magnetizable armature 35 is separated from the cores 33, 34 by equal distances. In this position the armature 35 is also out of engagement with either of the pairs of contacts 38 or 39 which are connected to the subdivided battery 31 and the circuit conductors 30, 32 in a similar manner to the spring switches 28, 29 of Fig. 3. The connections of the windings 19, 20 of the relay device are such that positive impulses supplied to either of these windings will cause the armature 35 to be repelled by the core 33 or attracted by the core 34 as the case may be, so as to close the contacts 38, and thus connect the left section of the subdivided battery 31 to the circuit conductors 30, 32. A negative impulse transmitted to either of the windings 19, 20 will cause the armature 35 to be repelled by the core 34 or attracted by the core 33 respectively so as to close the contacts 39 and connect the right section of the subdivided battery 31 to the local indicator circuit. The dial indicators are of the same kind as those in Fig. 3.

The modification shown in Fig. 5 is very similar to that described with reference to Fig. 3, except that each of the windings 19, 20 is mounted on a separate magnetizable core 40, 41 similar to the core 21 of the arrangement shown in Fig. 3. The magnetized contact arm 42 of the core 40 is arranged to close one or other of a pair of contacts 43, 44 so as to connect either the right or left section of a subdivided battery 49 to the circuit conductors 30, 32 of the local dial indicator circuit according as the impulse received by the winding 19 is a positive or negative impulse. The magnetized contact arm 45 of the core 41 is similarly arranged to connect pairs of contacts 46 or 47 controlling the subdivided battery 48 in the same manner so that the system operates as already described with reference to Fig. 3, except that separate cores for the windings 19, 20 are provided and separate sets of contacts 43, 44 are employed to supply impulses to the local

indicator circuit from independent sources of current 48, 49. The dial indicators, in this case again, are of the same kind as those in Fig. 3.

I have illustrated and described preferred and satisfactory constructions, but obviously changes could be made within the spirit and scope of my invention.

What I claim as my invention and desire to secure by Letters Patent is:—

1. The combination of secondary clocks constructed to be actuated by impulses alternately opposite in sign, normally-open local circuits for said secondary clocks, means for reversing the polarity in said local circuits, a plurality of main circuits for controlling the operation of said means, and a master clock in each of said main circuits for periodically closing, and alternately reversing the polarity therein.

2. The combination of secondary clocks constructed to be actuated by impulses alternately opposite in sign, normally-open local circuits for said secondary clocks, sources for delivering impulses opposite in sign in said local circuits, relay means associated with each of said local circuits and adapted to control the delivery of said impulses, a plurality of main circuits for said relay means, a source for delivering impulses opposite in sign in each of said main circuits, and a master clock in each of said main circuits and adapted to control said source to deliver impulses alternately opposite in sign.

3. The combination of secondary clocks constructed to be actuated by impulses alternately opposite in sign, normally-open local circuits for said secondary clocks, split batteries for supplying current to said local circuits, switches for connecting opposite sides of said batteries in their respective circuits, relay means for closing said switches, a plurality of main circuits for said relay means, a split battery for supplying current to each of said main circuits, and a master clock adapted to alternately close the circuit through opposite sides of the split battery in each of said main circuits.

4. The combination of secondary clocks constructed to be actuated by impulses alternately opposite in sign, normally-open local circuits for said secondary clocks, a plurality of sources of electro-motive force in each of said local circuits, a plurality of relays for controlling the closing of said local circuits, main circuits for said relays, and master clocks included in said main circuits.

5. The combination of secondary clocks constructed to be actuated by impulses alternately opposite in sign, normally-open local circuits for said secondary clocks, a plurality of split batteries in each of said local circuits, a pair of switches for closing the circuit through opposite sides of each of

said batteries, a relay for controlling the closing of each of said switches, a main circuit for each of said relays, a split battery in each of said main circuits, and a master 5 clock for alternately closing circuit through opposite sides of the split battery in each of said main circuits.

In testimony whereof I have signed my name to this specification in the presence of two subscribing witnesses.

LEONARD JAMES ARON.
